DUPLEX RAIL DELAY MECHANISM

Lester M. Walden, Chicago, Ill., assignor, by
mesne assignments, to Teletypesetter Corpora-
tion, a corporation of Delaware

Application December 29, 1933, Serial No. 704,467

40 Claims. (Cl. 199—29)

This invention relates to linecasting and composing machines and more particularly to automatic control mechanisms for operating machines of this class and similar keyboard controlled devices.

The present invention is an improvement upon the mechanism disclosed and described in co-pending application Serial No. 600,606, filed March 23, 1932, and has as its object the provision of mechanism embodied in an automatic control unit for linecasting machines whereby certain special functions or operations which are inherently slower in performance than are the most frequently executed functions will be controlled from a control medium but will be delayed, pending the performance of other functions of the machine and/or mechanism.

In the control of linecasting and composing machines, most functions are concerned with the selective release of matrices from their respective channels in a storage magazine after which they are permitted to gravitate to a lower level and be assembled in a carriage device known in the art as a matrix assembling block. Each matrix is customarily provided with two related character impressions or intaglio located one above the other in the operative position of the matrix, while the assembling block is provided with a shiftable or displaceable upper level supporting rail which, by its presentment or withdrawal from the ingress portion of the assembling block, may be made to determine the position in which subsequently received matrices shall thereafter be supported within the block. The position of each matrix, once determined by the condition of the aforesaid shiftable rail, prevails throughout the composing operation and until an assembled line of matrices is thereafter transported to the casting mechanism.

A certain time interval is required from the instant during which a matrix is released until the instant at which it is received in the assembling block. As a result, when it is desired to effect the movement of the assembling block slide rail following the reception of a certain matrix to vary the manner of reception of the next matrix or matrices, means must be provided for suspending the movement of the rail until the preceding matrix has had time to complete its travel and be properly received in the assembling block. Otherwise, with a spontaneous movement of the rail the reception of the preceding matrix might be effected in a position other than the one intended for it. It is accordingly a feature of the present invention to intro-

duce a time delay period equivalent to or exceeding the time necessary for the travel of one matrix from its storage magazine to the assembling block before the shiftable rail is operated to receive the next matrix or matrices.

This problem has been recognized before, various means having been provided for effecting this time delay, among which one method was to insert a suitable number of blank signals before each rail shift signal in the control tape. The effect of a blank signal is the mere idle operation of the record sensing mechanism, no functional response resulting therefrom, so that a proper number of blank signals intervening the last matrix selecting signal and each rail shift signal would effectively accomplish the desired object. This method may be considered objectionable because the introduction of blank signals into the tape requires a conscious effort and a certain degree of caution on the part of the tape perforating operator, and for the further reason that the inclusion of a certain number of blank signals before each rail shift signal, particularly in cases where a rail shift signal is frequently used, produces an unduly lengthened control form as compared with that otherwise required for the essential control signals.

While this invention is explained and described herein as applied to the rail shift function, it should be understood that the principles thereof are equally applicable to other functions having similar or related requirements.

A feature of the present invention is the provision of a variable time delay interval that may be measured in terms of units so that the total time delay may be considered as an aggregate predetermined number of time delay unit intervals.

In a control unit of the construction shown in the above identified application, a portion of which is illustrated in the accompanying drawing, there are provided a set of feeler levers which carry tape sensing pins. The pins of these levers are simultaneously presented in a transverse alignment to a tape which carries various transverse rows of perforations. The arrangement of the perforations is sensed by the feeler levers through their sensing pins and is thereafter transferred to a corresponding set of notched code bars. The notches of these code bars are so arranged that for each permutable position of the several bars, an individual alignment of the notches is afforded transversely. A plurality of selectable pull bars located adjacent the code bars are adapted to be moved into an operative position when the alignment of notches

is so disposed to select a particular one of them. After being moved into selected position, each of the pull bars may then be moved by a common actuator to perform a particular function to which 5 the pull bar is specially delegated. The several functions vary, such as matrix release operations, elevator operations, etc. Two of such functions are employed in connection with the illustration of the present invention for shifting a movable 10 assembling block supporting rail which may accordingly determine the position in which subsequently released matrices are received within the linecasting machine assembling block. In order to permit previously released matrices sufficient 15 time in which to descend to the assembling block from their source of origin in the matrix magazine, the response of the mechanism which moves the shiftable rail must be delayed for a predetermined time interval and the record reader 20 mechanism which senses the tape must also be momentarily arrested to permit this interval of delay.

These features are obtained by the provision of a ratchet feed mechanism comprising a toothed 25 element and an adjustable stop member. The ratchet feed element is released at the conclusion of each operation and is normally spring urged towards its zero position. The mechanism is driven from a constantly rotating shaft which 30 forms part of the record reader operating unit. Upon the reception of certain ones of predetermined signals whose response is to be delayed, there is immediately brought about the mechanical selection of a blocking lever which there- 35 upon blocks the further operation of the tape advancing mechanism while permitting the continued rotation of the record reader operating shaft which is then translated into so many consecutive ratchet feeding operations. These 40 operations continue until a pin carried by the ratchet feed mechanism causes a restoring arm to move which disturbs the selection mentioned above, displacing the blocking arm and permitting the reengagement of the tape advancing 45 mechanism. Normally, a special code bar is presented into its blocking position, and is located alongside the several selector code bars resembling them in all respects except that in place of the variously coded or notched edges, it is cut away 50 opposite each of the general class of selective elements, but is provided with a lug opposite those elements only whose functions are concerned in the delay effected by the present invention. As a result, in accordance with each selec- 55 tion which is to be delayed, when the several general code bars are properly positioned to permit the selective movement of such elements, the special bar referred to remains presented so as to block the selection.

60 Upon the restorative movement of the apparatus, a projection carried by one of the levers serves to displace the special or blocking code bar, consummating the selection of the predetermined element and its resultant functional 65 operation. In this manner the response to a particular selecting signal is delayed for a certain interval that may be measured by the number of revolutions made by the record reader operating shaft which intervene the initiation of the delay 70 mechanism and its subsequent restoration.

As a further incident of the present invention, it should be noted that by means of this mechanism the initiation of any function may be delayed for a predetermined interval, and upon 75 the initiation of the function, the performance

thereof may proceed at the customary or prevailing operating speed.

For a better understanding of this invention, reference may be had to the accompanying drawing in which like identifying characters represent similar parts throughout. In the accompanying drawing,

Fig. 1 is a perspective view of a portion of the record reader mechanism corresponding to that disclosed in copending application Serial No. 600,606 referred to above, and the assembling block with the shiftable rail associated therewith illustrating the present invention applied thereto;

Fig. 2 is a transverse section through a portion of the record reader showing a condition of operation of the ratchet feed or tolling mechanism embodying the present invention;

Fig. 3 is a fragmentary transverse section taken on a similar plane to Fig. 2, but illustrating another condition of operation;

Fig. 4 is a detail view of a fragment of the control form such as may be used in a machine of this class illustrating particularly two of the signal operations which initiate the Bold and Roman shift operations and upon the reception 25 of which the present invention is brought into play in accordance with this disclosure.

Automatic control devices of the class to which the present invention is particularly applicable are customarily controlled by means of a continuous paper web 11 fed through the medium of a sprocket wheel 12 which engages a central row of perforations 13. Coded signals are composed upon the tape or control form 11 in an arrangement of variously distributed perforations 14 transversely aligned with respect to the web. The sprocket 12 is carried by a shaft 15 upon which is also mounted a ratchet wheel 16 through which motion is received by the engagement therewith of a reciprocally moving pawl 17. The latter is carried upon a lever 18 which, as best indicated in Fig. 3, is pivoted at 19 upon a stud shaft secured to the framework of the record reader 21, by which term the entire mechanism is generally referred to. A spring 22 tends at all times to maintain lever 18 in its clockwise extremity or with its opposite projection 23 in abutting relation to an adjusting screw 24. The screw 24 passes through one arm of a lever 25 also pivoted on shaft 19 and provided at its extremity with a follower roller 26 with which it engages the periphery of a cam 27 to be referred to hereinafter as the tape feeding cam.

The tape feeding cam 27 is secured to a shaft 28 which, as may be discerned from the copending application referred to, is continuously rotated by means of a driving connection with a suitable source of power. Shaft 28 also carries a cam 29 that functions to periodically withdraw the tape sensing elements, about to be described, and a cam 31 which reciprocates the signal transferring elements in timed relation with the sensing operation.

The tape sensing elements, in accordance with the present embodiment, comprise a series of six 65 feeler levers 32 supported in a transverse alignment and pivoted upon a shaft 33. Individual spring elements 34 urge the several levers 32 in a counterclockwise direction so far as their travel is permitted by the stop shaft 35 which engages the side walls of a central perforation 36 in each of the levers. Feeler pins 37, one of which is provided with each of the levers 32, are aligned transversely so that when the several levers 32 tend to assume their counterclockwise extreme 70 75 80 85 90 95

position, each pin 37 is brought into registration with a predetermined position of the tape 11, whereat a perforation may or may not occur in accordance with each set of perforations constituting a particular code.

Where a pin 37 encounters a perforation, its lever 32 is permitted to rotate a few degrees farther, as illustrated by the foremost lever in Fig. 2, in which case its right-hand projection 38 is 10 presented to register opposite an abutment 39 of a transfer lever 41 associated with it. In such a case, the left-hand projection 42 of the particular lever is displaced rightwardly so as to avoid registration with its associated abutment 43 of lever 15 41. On the other hand, if the pin 37 encounters an area in the surface of the control form 11 that has not been perforated, its lever 32 is thereby prevented from rotating the full distance, but is 20 permitted to assume instead a position such as the one exemplified by the rearmost lever 32 in Fig. 2, in which case its left-hand projection 42 is maintained in registration with the abutment 43 of its associated transfer lever 41, while its right-hand projection 38 clears the abutment 39 with 25 which it is associated.

The several levers 32 are simultaneously brought into engagement with the tape 11 during a portion of each operative cycle, and they are likewise simultaneously withdrawn from such engagement by means of an operating bail 44. The latter is pivoted upon a shaft 45, Fig. 1, and is urged in a clockwise direction by a relatively weak spring 46. At an instant during each operating cycle when the feeler levers 32 are to be withdrawn 30 so that the tape 11 may be advanced, the apex of cam 29 encounters a follower roller 47 which is carried by one arm of a yoke 48. Through a projection 49 of yoke 48, the movement imparted by cam 29 is transmitted through the medium of a 35 relatively stiff compression spring 51 to a projection 52 integrally formed with bail assembly 44. While spring 51 is rigid enough to transmit the reciprocal motion for withdrawing the several feeler levers from engagement with the tape periodically, it does, nevertheless, constitute a yieldable connection intermediate the operative linkage, so that in the event of any impairment with the free movement of the delicately constructed levers 32, the motion imparted by cam 29 may be 40 absorbed within the spring element 51, thereby sparing any danger of rupture to the tape sensing elements which follow subsequently in the operative train.

When the several levers 32 are variously positioned in accordance with a particular code combination as determined by the perforations in the tape 11, their projections 38 and 42 are correspondingly arranged. Promptly thereafter the apex of cam 31 encounters a follower roller 53 45 of a bell crank assembly 54 which is provided with an adjustment screw 55 for varying the intermediate angle between its arms 56 and 57, the latter of which is bifurcated and is provided with a shaft 58 upon which are pivotally supported the several transfer levers 41 mentioned above. The motion originating from cam 31 is transmitted as a counter-clockwise torque to bell crank 54, causing the several transfer levers 41 carried by its arm 57 to be forced into engagement with 50 the projections 38 and 42 of the associated feeler levers 32, Fig. 3. As a result of this movement, those levers whose projections 38 are in registration with the lugs 39 of their transfer levers 41 cause a clockwise motion to be imparted to the 55 latter members, while those whose alternative

projections 42 and the lugs 43 are brought into forcible engagement, cause an opposite movement to be imparted to their transfer levers 41. This motion received by the levers 41 is directly transmitted through the disc and socket connections 59 to corresponding ones of a set of code bars 61 which are variously notched so that upon each permutative position of the several of said bars 61, a certain alignment of said notches is afforded to one of a plurality of selectable elements 62. 10 In this manner a particular element 62 thus selected is operatively conditioned and subsequently receives motion from a suitable source whereby it completes its particular function.

Of the several elements 62, two which are particularly concerned in connection with the present disclosure, are indicated 63 and 64. Upon the selection of either of these, their movement is transmitted through either of a pair of levers 65 and parallelogram assembly 66 to a link 67 15 which acts upon a bell crank 68 in cooperation with spring 69 to shift the rail 71 into one or another of its alternative positions, as explained above.

As thus far described, the movement of rail 71 follows in rapid succession the sensing of a rail shift signal by the several feeler levers 32, and it is the purpose of the present invention, following the reception of either type of shift signal of which there are two kinds, as indicated in Fig. 4, upon being sensed by the several levers 32, to delay the movement of the rail 71 for an interval of time that will suffice to permit any matrices which have been released by a signal preceding such shift signal to descend from their point of release in the magazine and be received in the assembling block 72 under the preceding conditions of the shiftable rail 71.

As illustrated in the present embodiment, the signal received by the several transfer levers 41 is not directly imparted to the code bars 61 but is, instead, transmitted through the medium of an intervening set of slide bars 73, each of which is provided with a notch 74. The several notches 74 are so arranged that upon the reception of either a Bold or Roman rail shift signal, they are brought into transverse alignment, affording thereby a clearance for a rod 75 which is superimposed thereover and seeks at all times to descend into said clearance. When, following the reception of either of these signals, rod 75 is 40 permitted to descend, a lever 76 to which the rod 75 is secured is thereby permitted to rotate counter-clockwise in response to the urge of its spring 77, Fig. 2.

An upstanding arm 78 of lever 76 is not at all times free to move, however, because of the obstruction in its path by a projection 79 which is formed on an arm 81 that extends downwardly and rightwardly, as viewed in Figs. 2 and 3, and is integrally formed with tape feed lever 82, described above in connection with the tape feeding mechanism. For this reason, lever 76 may not be moved counter-clockwise about its pivot 82, Fig. 2, except when the tape feeding lever 82 is in its upward extremity, as illustrated in Fig. 3, at which time the end of arm 78, moving behind projection 79, prevents the return of lever 82, causing the latter to be suspended in a position such as is illustrated in Fig. 3 and suspending thereby the further feeding of the control form or tape 11.

Arm 78 also carries a pin 83 which, during normal conditions of operation, Fig. 1, abuts the surface of an off-set of feed pawl 84 pivoted at 75

- 85 to an extended portion 86 of lever 25 and influenced leftwardly by a pawl spring 88. While the further reciprocation of tape feed lever 18 is suspended by the intervention of blocking lever 5 16 whose upstanding arm 78 now underlies the projection 79, the principal operating lever 25 is not thereby impaired, but is, instead, permitted to continue to reciprocate under the influence of cam 27 and a return spring 87.
- 10 The reciprocating movement of lever 25 is at all times imparted to pawl 84, but since during the normal condition of operation the latter member is blocked by pin 83, its efforts are ineffectual until, upon the selective movement of 15 blocking lever 76, pin 83 is withdrawn, permitting lever 84, in response to its spring 88, to be moved inwardly so that its tooth 89 may come into engagement with a ratchet wheel 91, which forms part of an integral assembly that also includes shaft 92 and associated ratchet wheel 93, Fig. 1. Into the latter member is adapted to engage the tooth of a detent pawl 94 which is also withheld from engagement during normal conditions by means of sidewardly extending arm 95 which engages at the rear of lever 84, making lever 94 thereby dependent for its clockwise motion upon the freedom of lever 84.
- A clockwise torque is imparted to shaft 92 by a helical spring 96 carried at the rearmost portion 30 thereof, Fig. 1, compelling shaft 92 to seek clockwise rotation until a stop arm 97, which is angularly adjustable on shaft 92, encounters a stop pin 98, suitably anchored in the framework. After being allowed to engage the ratchet wheel 35 91, the further reciprocation of lever 84 causes shaft 92 to be rotated counterclockwise the angular equivalent of one tooth distance, in terms of the teeth on wheel 91, for each reciprocal movement of lever 84, which is also indicative of a 40 cycle of rotation of shaft 28, as explained above. Shaft 92 is held in its position after being advanced by pawl 84 through the instrumentality of detent pawl 94, until after a predetermined number of operations, when a pin 99, which is 45 secured at the side of ratchet wheel 91, encounters a sidewardly extending projection 101 of a lever 102 idly carried upon shaft 92, which passes through a pair of ears 103 integrally formed therewith.
- 50 The engagement of pin 99 with projection 101 imparts counterclockwise rotation to lever 102, causing an abutment screw 104, which is carried thereby, to engage a lever 105, Fig. 3. This lever generally resembles one of the feeler levers 32 55 except that it is not provided with the sidewardly extending portion nor with the feeler pin 37 carried thereby. Preferably, lever 105 is carried intermediate the six feeler levers 32 and is adapted by its projections 38 and 42 to transfer a signal 60 condition through a transfer lever 41 especially assigned to it to a slide bar 106, in the same manner in which any of the bars 32 transfer their settings to their associated bars 73 and 61. Bar 106 65 resembles the general class of bars 73 in shape, but is articulated to a special code bar 107 which differs somewhat from the general class of permutation code bars 61. As will be seen in Fig. 1, bar 107 is cut away opposite all of the positions in which the other bars are provided with variously coded blocking projections, except at 108 and 109 whereat it is provided with blocking projections. Projection 108 is normally presented so 70 as to block the selection of element 64 and projection 109 is normally presented to block the 75 selection of element 63, so that upon the reception

of either of the code signals illustrated in Fig. 4, though the remainder of the code bars 61 may be moved into proper position for selecting either of the elements 63 or 64, their selection will nevertheless be blocked by the intervention of 5 special bar 107.

Meanwhile, however, when screw 104 of lever 102 engages the special signal lever 105, it moves the latter from its normal position, during which its projection 38 registers opposite lug 39 of its transfer lever 41, to its alternative position when its projection 42 comes into registration with lug 43 of lever 41. Thereafter, upon the transfer operation of lever 56, the bar 106 and bar 107, 10 acting as a unit, are moved leftwardly as viewed 15 in Fig. 1, withdrawing the projections 108 and 109 and permitting the particular one of elements 63 or 64 (depending upon whether the shift signal is Bold or Roman) to be selected.

The movement of bar 106 not only effects the 20 movement of code bar 107, but also through its notch 74 which is then urged out of transverse alignment, causes to be cammed out the rod 75 which is carried by lever 76. This restores the latter to its normal position, withdrawing the 25 upper extremity of its arm 78 that had been presented under projection 79 and had been blocking lever 18. At the same time pin 83 is moved into the path of off-set pawl 84, disengaging the latter from the ratchet wheel 91. Lever 84, through its 30 engagement with the sidewardly extending arm 95, also withdraws the detent pawl 94, causing shaft 92 to be restored to normal position under the influence of spring 96. Shaft 92 then rotates in a clockwise direction until it arrives at the 35 position when its stop arm 97 again engages stop pin 98.

With the restoration of shaft 92, pin 99 carried by wheel 91 is withdrawn from engagement with projection 101 of lever 102. This retracts 40 screw 104 from contact with special lever 105 and permits the latter to again assume its normal position, into which it is constantly urged by an individual spring 34 associated with it in the 45 same manner as similar springs are associated with the general class of feeler levers 32. Thus upon the succeeding sensing operation by the several levers 32, special lever 105 assumes its normal position which, when transferred to code bar 107, restores it so as to effect the blocking of 50 levers 63 and 64 in readiness for a subsequent rail shift signal operation.

It will be noted that the delayed operation affects two of a plurality of automatically controlled functions and that the time interval of 55 delay may be varied by adjusting the angular position of stop arm 97, or in other words, by permitting a variable number of teeth to intervene between the normal position of shaft 92 and the position thereof at the time when pin 99 moves 60 the restoring lever 102.

Description of operation

Under normal conditions of operation, the tape 11 is fed leftwardly as viewed in Fig. 4, by the 65 sprocket feed wheel 12. Record reader operating shaft 28, through its cam 27, imparts reciprocal motion to an assemblage of levers which are pivoted at 19 and which include lever 25 and lever 18. The latter receives its counterclockwise movement through the engagement of its projection 23 with the adjustment screw 24 carried by the principal operating lever 25. The return movement of lever 18 is influenced by its associated spring 22 and in this manner lever 18 is capable 75

of actuating the tape feed shaft 15 through the instrumentality of its feeding pawl 17.

When pursuant to one of the special signals such as in the present illustration the Roman 5 face or Bold face shift signals, shaft 15 is received within the alignment of notches 74, lever 76 is rocked about its pivot 82 causing to be withdrawn the pin 83 which normally prevents pawl 84 from engaging ratchet wheel 91 and concurrenly 10 presents the upper extremity of arm 78 behind the projection 79 which is an integral formation of lever 18. In this manner, either of the special selecting signals arrest the further activity of the tape advancing lever 18, but the principal 15 operating lever 25 continues reciprocating under the influence of cam 27 and spring 37. This motion is imparted to pawl 84 which now being permitted to engage ratchet wheel 91 rotates the latter and also shaft 92 in a counterclockwise direction, as viewed in Figs. 2 and 3. Each reciprocal movement of pawl 84 advances the ratchet wheel 91 one tooth distance, where it is held by detent pawl 94 while pawl 84 returns to engage a succeeding group in the wheel 91. 20 This operation continues until the pin 99, which extends sidewardly from wheel 91, comes into engagement with the projection 101 of a restoring lever 102, moving the latter counterclockwise about shaft 92 until screw 104 engages and moves lever 105, as viewed in Fig. 3. During all of the time that pawl 84 is rotating shaft 92, the several transfer levers 41 are reciprocated to and fro by their carrying bail and lever 54 which is influenced by cam 31. Since, however, no change 25 is effected in the several feeler levers 32 or 105, the movement of the transfer levers 41 have no further effect until the instant when screw 104 dislodges the special lever 105, causing the associated transfer lever 41 thereof to shift its connecting bar 106 and code bar 107. The movement of these two bars dislodges shaft 75 and associated lever 76, also withdrawing bar 107 from blocking the partially selected element 63 or 64, as the case may be. This causes the common 30 actuator to engage the selected bar 63 or 64 and to perform the particular function for which it was selected.

The return of lever 76 restores the mechanism in the record reader to normal condition, permitting tape feed lever 18 to again be influenced by the principal operating lever 25, dislodging feed pawl 84 from engagement with ratchet wheel 91 and through it withdrawing the detent pawl 94 so that shaft 92 may yield to the influence of 35 spring 96 and be restored to its normal position which, as explained above, is angularly adjustable and dependent upon the angular position of stop member 91 with respect to shaft 92.

In the particular case, the function whose response is delayed by the described mechanism is the rail shift operation, as already explained. 40 When bar 63 is selected, it rotates its associated lever 65 clockwise, as viewed from above in Fig. 1, causing the parallelogrammatic assembly 66 to pull link 67 downwardly and present rail 71 in its Bold position, causing subsequently received matrices to be supported by the rail 71, but when thereafter bar 64 is selected, it likewise rotates its associated lever 65 clockwise but affects 45 the parallelogrammatic assembly 66 in a contrary manner, thrusting link 67 upwardly so as to permit spring 69 to withdraw the shiftable rail to its Roman position.

The amount of time that is to lapse between the 50 instant at which the particular rail shift signal is

received and that at which the rail is actually shifted may vary somewhat with the variations in font that may be used in a particular job or composition. To adjust for this contingency, stop arm 97 is moved axially with respect to shaft 92, introducing a relatively greater or fewer number of teeth between the normal position of shaft 92 and the angular position at which pin 99 effectively moves the restoring lever 102. This feature of adjustability permits not only for varying the time delay in connection with a particular function of shifting the rail, but also permits the use of the same delay mechanism for various other functions, the time delay intervals of which may vary materially. 10

A further noteworthy feature of this invention is its capacity to subserve any or so many of the control functions as may be desired. To accomplish this object, bar 107 need only be provided with the proper projections such as 103 and 109 to effect the blocking of any of the elements 62 whose functional response it is desired to delay. 15

While the present invention has been illustrated and described with specific reference to a particular adaptation thereof, it should be understood that numerous modifications and variations may be made without departing from the spirit or scope of this invention. It is therefore intended not to be limited to the particular language of the foregoing description nor to the details in the accompanying illustrations but to be permitted, instead, a latitude of interpretation as indicated by the hereunto appended claims. 20

What is claimed is:

1. In a linecasting and composing machine, the combination of an assembling block for receiving selectively released matrices from which a printing slug is to be cast including a rail shiftable into two positions to accordingly support or reject subsequently received matrices, apparatus for shifting said rail, a record reader responsive to various signals stored in a tape, and adjustable means operatively associated with said record reader and specially responsive to rail shifting signals received thereby for delaying the effectiveness of said signals for a predetermined interval that may be varied in accordance with predetermined adjustment. 35

2. In a tape sensing mechanism, a set of feeler elements, an intermittently operative tape feeding apparatus, a cam shaft including a cam for operating said elements and a cam for operating said apparatus, and means for suspending the movement of said apparatus without arresting said shaft. 50

3. In a tape sensing mechanism, an intermittently operative tape feeding apparatus, a rotating cam shaft including a cam secured thereto for operating said apparatus, and means for suspending the movement of said apparatus without arresting said shaft. 55

4. In a tape sensing mechanism, an intermittently operative tape feeding apparatus, a cam for actuating said apparatus, and means for suspending the movement of said apparatus without arresting said cam. 60

5. In a tape sensing mechanism, a set of feeler elements, an intermittently operative tape feeding apparatus, a cam shaft including a cam for operating said elements and a cam for operating said apparatus, and means for suspending the movement of said apparatus comprising a blocking lever for withholding said apparatus from receiving motion from its operating cam. 70

6. In a tape sensing mechanism, a set of feeler 75

- elements, an intermittently operative tape feeding apparatus, a cam shaft including a cam for operating said elements and a cam for operating said apparatus, and means for suspending the 5 movement of said apparatus comprising a member responsive to certain control signals in the tape by moving into position for blocking the operative engagement between said apparatus and its cam.
- 10 7. In a selector mechanism, a timing device comprising a selector operating shaft capable of continuous rotation, a trip-off lever for performing an occasional function, a ratchet wheel having a lug for engaging and actuating said lever, 15 and a pawl for feeding said wheel under the propulsion of said shaft.
8. In a record reader mechanism, a set of coded selector elements to be variously positioned for effecting the individual selective conditioning of 20 each of a plurality of function elements, a set of signal sensing members, means for moving said selector elements to correspond with the settings of said members immediately following a sensing operation of said members, and means for 25 moving said selector elements to correspond with the settings of said members after a predetermined time delay interval.
9. In a record reader, an escapement mechanism to be initiated for occasional or periodic performance including a continuously operative shaft, a tributary shaft, means for rotating said tributary shaft under the control of said continuously operating shaft comprising a pawl and ratchet wheel assembly, a trip-off lever loosely 35 supported upon said tributary shaft, means responsive to certain signals for effecting the operative connection of said pawl and ratchet mechanism, and an engagement means carried by said tributary shaft for actuating said lever upon 40 summation of a predetermined revolution of said tributary shaft.
10. In an automatic control device, a set of signal responsive elements, a set of selector bars positioned by the setting of said elements, and an escapement mechanism responsive to certain settings only of said elements comprising a shaft, a trip-off means carried by said shaft, and a feed pawl for rotating said shaft intermittently and for thereby advancing said trip-off means.
- 50 11. A record reader mechanism including a continuously rotating power transmitting element, oscillatory record advancing mechanism intermittently actuated by said element, a set of sensing elements responsive to signal conditions 55 carried by the record material, and means responsive to a certain condition of said sensing elements for dissociating said oscillatory record advancing mechanism from said continuously rotating element.
- 60 12. In an automatic control device responsive to transverse perforations in a tape, the combination including a set of tape sensing elements, a set of code bars corresponding to said elements, means for transmitting the condition of 65 said elements to said code bars, an additional code bar, a lever for controlling the positioning of said additional code bar having a normal position, means for altering the position of said lever including a ratchet feed mechanism responsive 70 to a predetermined number of advancing operations, and means actuated by said ratchet feed mechanism for displacing said lever after the consummation of said predetermined number of ratchet feeding operations.
- 75 13. In an automatic selector mechanism, a set of notched permutation elements, a plurality of function performing members to be individually conditioned by the variable placement of said elements, means responsive to certain signals for summarily placing said elements to select one 5 of said members, and means responsive to certain other signals for placing said elements after the lapse of a predetermined time interval.
14. In a signal responsive selecting apparatus, a plurality of function performing elements to 10 be individually conditioned for operation, a set of coded selectors capable of variable placement for conditioning said elements individually, a set of signal responsive elements corresponding in number to said selectors for placing said 15 selectors, and means for deferring the selective conditioning of certain of said plurality of elements until the lapse of a predetermined interval after the corresponding placement of said 20 selectors.
15. In a signal responsive selecting apparatus, a plurality of function performing elements to 25 be individually conditioned for operation, a set of coded selectors capable of variable placement for conditioning said elements individually, a set of signal responsive elements for placing said 30 selectors, and means for deferring the selective conditioning of certain of said plurality of elements until the lapse of a predetermined interval after the placement of said selectors.
16. In a record reader mechanism, a plurality of function elements subject to selective conditioning and operation, a set of code members variously presentable for selectively conditioning 35 said elements individually, a corresponding set of signal responsive means for variously presenting said code members, and means for suspending the selective conditioning of said function elements during a predetermined time interval following the proper presentation of said 40 code members.
17. In an automatic control device, a set of standard selecting elements, a special selecting element, and means responsive to a setting of 45 said standard elements for positioning said special element including an actuating member having a plurality of teeth, and means for varying the number of teeth to intervene between the normal position of said member and the position at which it affects said special element. 50
18. In an automatic control apparatus responsive to various perforations in a tape, a tape advancing mechanism including a feed sprocket, a reciprocating element for feeding said sprocket, and a power driven shaft for actuating said reciprocating element, a spring for urging said element into engagement with said shaft, and a blocking means responsive to certain perforations in the tape for preventing the effort of said spring in effecting the engagement of said 55 element with said shaft.
19. In a selecting mechanism, a plurality of elements to be selected, a set of code bars variously notched and positionable to select said elements individually, an additional code bar 65 normally blocking the selection of certain of said elements, and a ratchet feed mechanism including means responsive concurrently with the selection of said certain of said elements and effective after the expiration of a predetermined delay 70 interval for withdrawing said additional bar and permitting the complete selection of said certain of said elements.
20. In an automatic control mechanism, means responsive to various perforations in the tape for 75

executing corresponding functions in a controlled mechanism, an operating shaft capable of continuous rotation for actuating said means, and a delay mechanism for suspending the operation 5 of said means under predetermined conditions including a step-by-step actuator, means for imparting motion to said actuator under control of said shaft, and a trip-off means carried by said step-by-step actuator.

10 21. In a record reader mechanism, a set of feeler levers, individual means for urging said feeler levers into engagement with the surface of a control form, means for withdrawing said feeler levers simultaneously from engagement with 15 said form including an operating shaft, a return bail, and a spring element intermediate said shaft and said bail for absorbing excessive and/or resisted forces imparted by said shaft.

22. In a record reader mechanism, a plurality of 20 elements to be individually selected and operated, a set of code bars variously positionable to select said elements, means responsive to certain positions of said code bars for delaying the selection of those elements affected by said conditions including a blocking member normally disposed to 25 prevent the selection of certain ones of said elements, a ratchet feed mechanism initiated by said certain positions of said code bars, and means actuated by said ratchet feed elements after a 30 predetermined delay interval for withdrawing said blocking member.

23. In a mechanical selecting apparatus, a plurality of function performing members, a set of code bars transversely disposed with respect 35 to said members and having notch and lug cooperation therewith whereby for each disposition of said set of bars a selective clearance is offered to one of said members, auxiliary portions to said bars having notches corresponding in permutative arrangement to certain ones of the notches for selecting corresponding ones of said members, and mechanism selected by the notches in said auxiliary portions for modifying the selective response of said certain ones of said members. 40

24. In a signal responsive apparatus, a set of notched selecting elements permutatively positionable to afford individual selective clearances, a corresponding set of signal responsive members for setting said elements in various arrangements during consecutive cycles of operation, an additional selecting element associated with said set of elements but having no associated signal responsive member, and means responsive to certain 45 conditions of said set of notched elements and functioning during the time interval of a plurality of said cycles of operation for setting said additional selecting element.

25. In an automatic control mechanism having 50 a plurality of individually selectable elements for performing a corresponding plurality of functions, the method of delaying the performance of certain of said functions beyond their normal response which comprises the steps of selecting an element for suspending the further operation of the mechanism, concurrently setting in motion a timed ratchet feed device, and through said ratchet feed device reinstating the 55 operation of said mechanism.

26. In an automatic control apparatus having a plurality of individually selectable elements for performing a corresponding plurality of functions and a mechanism for selectively conditioning each of said elements in accordance with con- 60

trol signals, the method of delaying the performance of certain of said functions which comprises the steps of blocking the selection of said certain of said elements which are associated with the functions to be delayed, setting in motion a ratchet feed device of preadjusted timing, permitting the partial selection of said certain elements in response to their selecting signals, and thereafter completing said selection through the instrumentality of said ratchet feed device. 10

27. In an automatic control unit responsive to tape storage signals for performing a plurality of control functions, a set of selecting bars having variously disposed notches therein designed to afford an individual selective clearance with each permutative arrangement, storage signal sensing means for setting said bars cyclically, an additional selecting bar, means for determining the position of said additional selecting bar in accordance with the setting of said set of selecting bars comprising, a ratchet feed mechanism initiated into operation in response to certain arrangements of said set of selecting bars, and means associated with said ratchet feed mechanism for moving said additional bar. 15

28. In a tape sensing apparatus for automatically controlling the performance of a plurality of functions, a set of primary signal element levers, means for setting certain of said levers in accordance with the perforations in a tape, and means for setting certain of said levers in accordance with a local operating mechanism. 20

29. In a tape controlled mechanism, a set of primary signal elements, a tape advancing means, apparatus for cyclically operating said tape advancing means and for permitting the setting of certain of said signal elements in accordance with the instant condition of said tape, and a device for changing the setting of certain of said elements without advancing said tape. 25

30. In an automatic control mechanism for the supervision of a plurality of functions under the control of perforations in a tape, a cyclically operative shaft, means under control of said shaft for advancing a perforated tape, a set of primary signal impulse levers, means for variously positioning said levers in accordance with the instant perforations appearing in said tape, a set of coded selectors, means under cyclic control of said shaft for positioning certain of said selectors in accordance with said primary impulse levers, and means operated by a plurality of cycles of said shaft for positioning certain others of said selectors. 40

31. In a tape sensing apparatus, a cyclically rotatable operating shaft, a tape advancing mechanism cyclically actuated by said shaft, a set of tape feelers constituting primary code storage elements, additional means also constituting primary code storage elements, transfer means operated cyclically by said shaft for communicating the condition of all said primary storage elements to a mechanical selector, means responsive to certain settings of said feelers for suspending the operation of said tape advancing mechanism, and a device for positioning said additional means under the actuation of a plurality of cycles of said operating shaft. 45

32. In a tape controlled apparatus, a cyclically operative power shaft, a set of code selector bars, 50 a corresponding set of primary impulse storage levers, a corresponding set of transfer levers reciprocated by said shaft for communicating the setting of said storage levers to their corresponding selector bars, a tape advancing mechanism, 55

and means for arresting the cyclic performance of said apparatus comprising a member for disabling said tape advancing mechanism while permitting the cyclic performance of said shaft and transfer levers.

33. In a tape sensing apparatus that is cyclically actuated by a power source to effect each signal sensing function, the method of achieving a delayed response in the execution of certain selective functions which comprises the steps of partially selecting a function initiating member, utilizing the cyclic actuation of said power source to actuate a ratchet feed device, and completing the selection of the partially selected member by the consummate movement of the ratchet feed device.

34. In an automatic selector mechanism, a plurality of function performing levers to be individually conditioned, means responsive to stored signals for conditioning said function performing levers, means for delaying the response of certain of said conditioning means, and means operable simultaneously with said certain conditioning means for discontinuing the operation of the delaying means.

35. In an automatic selector mechanism, a set of notched permutation elements, a plurality of function performing levers to be individually conditioned by the variable placement of said elements, auxiliary portions to said elements having notches corresponding in permutative arrangement to certain ones of the notches in said permutation elements for selecting corresponding ones of said levers, mechanism selected by the notches in said auxiliary portions for modifying the selective response of certain ones of said levers, and means operable upon modification of said selective response to cancel the selection at said auxiliary portions.

40 36. In an automatic control device, control form presenting means, selector means responsive to signals in said control form, means controlled by the selector means for interrupting said control form presenting means, means also controlled by said selector means for initiating selectively a multiplicity of operations, and means controlled by said operation initiating means for restarting said control form presenting means after an in-

terval commensurate with the time required for the performance of one of said multiplicity of operations.

37. In a signal responsive device, a set of code bars, a corresponding set of signal responsive elements each related to one of said code bars, means for positioning each code bar in accordance with its related element, an additional code bar, and means responsive to a condition of the several of said elements for positioning said additional code bar including a mechanism initiated by said certain condition of said several elements and operative after a predetermined adjustable delay interval.

38. In an automatic control mechanism having a plurality of individually selectable elements capable of performing individual functions, the method of delaying the performance of certain of said functions which comprises the steps of normally blocking the selection of said certain of said elements, permitting the partial selection of said elements in response to their selecting signals, and thereafter upon the termination of a predetermined adjustable time interval permitting the completion of the selection of said elements and their resulting selective operation.

39. In an automatic control device, signal presenting means, signal responsive means for partially initiating operations, means controlled by the signal responsive means for interrupting the signal presenting means, means for completing the initiation of operations, and means controlled by the last mentioned means for restarting the signal presenting means.

40. In an automatic control device, signal presenting means, signal sensing means, means controlled by the signal sensing means for interrupting the signal presenting means, code bars controlled directly by said sensing means for initiating operations, a code bar controlled indirectly by said sensing means, and means controlled by the last mentioned code bar for restarting the signal presenting means after an interval commensurate with the time required for the performance of an operation.

LESTER M. WALDEN.
